(57) **CLAIM**

The ornamental design for a combined box for storage of a tool for chip removing machining and torque key, as shown and described.

DESCRIPTION

FIG. 1 is a top view of the present invention.

FIG. 2 is a bottom view thereof.

FIG. 3 is a side view thereof.

FIG. 4 is a back view thereof.

FIG. 5 is the other side view thereof.

FIG. 6 is a front view thereof.

FIG. 7 is a top perspective view thereof; and,

FIG. 8 is a bottom perspective view thereof.
